UNITED STATES PATENT OFFICE.

HERMANN V. FENGLER, OF WEST PHILADELPHIA, PENNSYLVANIA, ASSIGNOR TO
UNDERWOOD TYPEWRITER COMPANY, OF NEW YORK, N. Y., A CORPORATION OF
DELAWARE.

TYPE-WRITING MACHINE.

1,299,403.

Specification of Letters Patent.

Patented Apr. 1, 1919.

Original application filed July 9, 1915, Serial No. 38,853. Divided and this application filed July 16, 1917.
Serial No. 180,729.

To all whom it may concern:

Be it known that I, HERMANN V. FENGLER, a citizen of the United States, residing in West Philadelphia, in the county of Philadelphia and State of Pennsylvania, have invented certain new and useful Improvements in Type-Writing Machines, of which the following is a specification.

This invention relates to an improvement 10 in typewriting machines, and more particularly to paper guides for properly feeding work-sheets of different widths to the platen of the typewriter. This case is a division of my application, Serial No. 38,853, filed July 15 9, 1915, (now Patent No. 1,256,303, dated February 12, 1918.)

In the parent case above-mentioned, the record sheet, after writing one bill or statement, was kept on the platen, and, by back 20 and forth rotation of the platen, the completed bill or statement was removed from the platen. The record sheet used was wider than the statement or bill sheet and the carbon sheet used with the latter, so that a new 25 bill or statement sheet could be inserted with the old record sheet for each new group of items.

For the purpose of leaving a space in back 30 of the record sheet left on the platen, guides are provided which have two guiding surfaces at different levels, the higher lever taking care of wider record sheets, while the lower level takes care of the narrower statement or bill sheet and the carbon sheet. 35 The difference in levels is provided by placing triangular blocks on the guides. The sides of the guides and the inner sides of the blocks form gaging surfaces to properly locate the record sheet and the bill sheet 40 relatively to each other and relatively to the platen.

The guides are separately shiftable toward and from each other to accommodate sheets of different widths, and may also be thrown 45 to inoperative positions to permit the ordinary paper table or shelf to be used in guiding the work-sheets onto the platen.

Other features and advantages will hereinafter appear.

In the accompanying drawings, 50 Figure 1 is a perspective view, showing the guides in their operative position in contact with the paper shelf.

Fig. 2 is a vertical section, taken from front to rear about midway of the platen, 55 showing in full lines one of the guides in its operative position, and in dotted lines the same guide in its ineffective position.

The invention is shown as applied to the Underwood typewriter, in which the usual 60 platen 1 is mounted on a carriage or platen frame 2. This carriage or platen frame comprises side plates 3 and a paper table or shelf 4. The paper shelf 4, for ordinary typewriting work, may guide work-sheets to the 65 platen 1, where they are gripped between the surface of the platen 1 and feed-rolls 5, coöoperating with the platen. The typewriting mechanism includes type-bars 6, which strike the platen at what is known as the 70 printing point.

The platen 1, as described in the parent case above-mentioned, receives line-space movements from a line-space mechanism 7, and also receives major back and forth rotations from a billing attachment, not shown 75 in this case. As shown in the parent case, this attachment is for the purpose of enabling a single record sheet to have typewritten thereon several different groups of 80 items, each group being written on a separate bill or statement sheet.

For the purpose of properly guiding the record sheet and the bill sheet with the intervening carbon sheet to the platen, and at 85 the same time permit the change of the bill sheet, while the record sheet is still on the platen, the bill sheet is made narrower than the record sheet, and guides 8 and 9 are provided for gaging and keeping the record 90 sheet and the bill sheet separate from each other at points short of the entrance to the platen 1.

The guides 8 and 9 are provided on their

opposite outer edges with vertically-extending sides 10 and 11, so as to form gaging surfaces to engage the side edges of the record sheet and direct it properly to the platen 1. When the record sheet is extending between these sides 10 and 11, it rests on raised surfaces 12 and 13 formed by triangular blocks 14 and 15, provided on the guides 8 and 9. The blocks 14 and 15 are located adjacent the sides 10 and 11 and away from the inner edges of the guides 8 and 9. That is to say, there is a considerable space between the inner sides of the blocks 14 and 15 and the inner edges of the guides 8 and 9. In other words, the guides 8 and 9 have a guiding surface of somewhat less width than the distance between the sides or gages 10 and 11, and at a lower level than the surfaces 12 and 13 of the blocks 14 and 15. This inner guiding surface is for the bill sheet and the carbon sheet, which are of less width than the work-sheet. The surfaces 12 and 13 conform, at their lower edges, with the lower level of the inner guiding surface, and gradually spread away therefrom to separate the second sheet from the carbon and bill sheets. From this description it will be observed that the surfaces 12 and 13 may be regarded as forming a wide chute open toward the platen, and arranged at the introductory side thereof and having side gages 10 and 11. Moreover, the surfaces of the guides 8 and 9 which lie flat upon the paper-table 4 may be regarded as forming the floor of a narrow chute also open toward the platen, and having side gages 14 and 15. The floors of these two chutes, as pointed out above, come together or merge into the paper-table. This arrangement of chutes form a collating board which enables a work-sheet to be laid upon the floor of the narrow chute through its open face, and a wider work-sheet to be later laid upon the floor of the wide chute through the open face of the latter chute.

By this means, after a bill or statement has been written on the record sheet and the bill or statement sheet, then the platen 1 can be reversely rotated to enable the removal from the platen of the bill or statement sheet and also the carbon sheet if desired, while the record sheet remains on the platen. This will leave considerable space in back of the record sheet, as the latter is supported by the surfaces 12 and 13 away from the guiding surfaces provided at the lower level of the guides 8 and 9. Thus the fresh bill or statement sheet with the carbon sheet can be dropped in back of the record sheet and advanced in unison with the record sheet to the printing point of the platen. This can be repeated several times for the same record sheet, removing, between the writing

of each bill, a completed bill and placing on the platen another bill or statement sheet 65 for a new group of items.

The guides 8 and 9 are pivotally mounted on brackets 16, which, in turn, are slidably and pivotally mounted on a rail 17, supported by the inner carriage or platen frame 70 2. Inasmuch as the brackets 16 are adjustable on the rail 17 toward and from each other, the distance between the sides 10 and 11 and the blocks 14 and 15 can be varied to accommodate record and bill or statement 75 sheets of different widths. When it is not desired to use guides 8 and 9, they can be swung up back out of the way to the dotted-line position indicated in Fig. 2, by swinging them about the rail 17 as a pivot. A 80 spring detent 18 is provided for locking each guide to the rail 17 to prevent accidental movement thereof.

Variations may be resorted to within the scope of the invention, and portions of the 85 improvements may be used without others.

Having thus described my invention, I claim:

1. The combination with a rotary platen and a paper table at the introductory side 90 of the platen, of two double level spacing guides mounted on said table in position to support the margins of a record sheet and space it from the table to facilitate the introduction or removal of narrower work-pieces 95 between said table and said spacing guides, said guides being relatively adjustable along the table to accommodate sheets of different widths, and the same having each a vertically extending surface adapted to guide 100 the side-edges of the record sheet.

2. The combination with a platen, of a paper shelf coöperating with said platen, and a pair of guides coöperating with said shelf, to direct work-sheets to said platen, 105 said guides facing inwardly toward each other, and each having two inclined steps with supporting surfaces at different levels and with vertical surfaces extending upwardly from said supporting surfaces, 110 whereby work-sheets of different widths are held separated from each other and said shelf at their tail edges, so as to enable one of the sheets to be replaced while the other remains on said platen.

3. The combination with a revoluble platen, of a wide chute having an open face toward the platen and arranged at the introductory side thereof, and a narrow chute opening out of the wide chute and also arranged at the introductory side thereof and included between the sides of the wide chute, 120 to enable a work-sheet to be laid in the narrow chute through the open face of the wide chute.

4. The combination with a revoluble platen,

of a narrow chute at the introductory side thereof, a wide chute also mounted at the introductory side of the platen, and a table into which said chutes merge together in the vicinity of the platen.

5. The combination with a revoluble platen, of a collating-board at the introductory side thereof, comprising an open-faced narrow chute having a floor and side-guides,

and also comprising an open-faced wide chute, said wide chute having floor portions bordering upon said side-guides and extending outwardly therefrom, and side-gages at the outer edges of said floor portions.
